ABSTRACT

A motor-driven time limit relay including electromagnetically controlled relay contacts, in which motor driving and contact control sections are separated by a base plate. The electromagnet of the contact control section is secured laterally to one side of said base plate. The yoke extends from an end secured to the electromagnet core to the other end, along upper face of the magnet and, at the extended end of the yoke, an armature is pivoted. A plate actuator likewise extends above the magnet and is coupled at one end to the armature for integral movement with the latter. The other free end of the actuator is normally biased to its lower position of the armature's de-attracted state. A sliding member for controlling the relay contacts positioned above the actuator is slidably mounted to a guide means secured to the other opposite end of the magnet to the armature, and is coupled to the free end of the actuator. Upward movement of the actuator free end at the time of armature attraction allows the sliding member to slide upward for relaying operation, but the sliding is normally locked by a locking lever secured to the guide means until a preset limited time reaches.

TIME LIMIT RELAY

This invention relates to time limit relays, and, more particularly, to an improvement in timers in which electric relay is operated at a limited time period.

In conventional motor-driven time limit relays, individual componential parts such as motor driving means, contact make-break means and clutch means are combined in complicated manners. Thus, if there occurs any trouble with any one of such parts, much time must be wasted for repairing works. Furthermore, such trouble may occur frequently due to a great number of parts used in the respective means.

According to the present invention, such disadvantages as above are eliminated by combining such parts into blocks and disposing such blocks in a rational way.

The primary object of this invention is, therefore, to provide a time limit relay, which is easy to assemble and inspect and is compact in size.

Another object of this invention is to provide time limit relay which has stable contact pressure and permits instantaneous ON-OFF operation of contacts.

Another object of this invention is to provide time limit relay which makes positive relational operation of a slider plate for driving contacts to a lock means for locking said slider plate during the period of limited time.

Still another object of this invention is to provide a time limit relay which has a clutch mechanism permitting positive engagement with a small force with a motor being driven and easy change of setting during the period of limited time with a small force.

The present invention shall now be explained in detail with reference to a preferred embodiment as illustrated in the attached drawings, in which:

FIG. 1 is a perspective view of a time limit relay of this invention;

FIG. 2 is a perspective view of the time limit relay of this invention with the case and mounting metal member removed;

FIG. 3 is a perspective view of terminal section as seen from the back thereof in FIG. 2;

FIG. 4A is a plan view of the time limit relay in FIG. 2, FIG. 4B is a left side view of the relay shown in FIG. 4A, and FIG. 4C is a right side view of the same;

FIG. 5 is a perspective view of contact make-break member with all components disassembled; and

FIGS. 6A and 6B, and FIGS. 7A and 7B are explanatory views of the operations of the time limit relay of this invention.

In FIG. 1, 1 is a dial case, 2 is a knob attached to said dial case, 3 is an indicator rotated with said knob, 4 is a case, and 5 is a mounting metal member.

FIG. 2 shows the time limit relay with the case 4 and the mounting metal 5 as removed from the dial case 1. 6 represents a body of the time limit relay.

FIG. 3 is a perspective view of a terminal section 9 as removed from the body 6. The body 6 is divided into a motor driving section A and a contact control section B which are coupled to each other by a base plate 7, on which they are mounted, respectively. The base plate 7 is joined to the dial case 1 by means of mounting metals 8. FIG. 5 chiefly shows a contact control mechanism with all parts disassembled. In FIG. 5, 10 represents an electromagnet, 11 is a coil bobbin, 12 is a core, and 13 is an L-shaped yoke fixed to said core 12. 14 represents armature mounting lugs provided on both sides at one end of the yoke 13. 15 represents an armature provided with cut-outs 16 on both side walls, said armature is rotatably mounted to the yoke 13 with the cut-outs 16 engaged with the lugs 14. 17 is a recess provided at the upper edge of the armature, into which the body of an L-shaped actuator 18 is set. Said actuator 18 is fixed to the armature 15 at a bent portion 19 by welding or some other means. 20 represents a projection of the actuator 18, likely 21 is a longitudinal slit, 22 is a forward end, 23 is a recess made at said forward end 22, 24 is a hole for engaging an end of a spring 26, and 25 is a stub-like projection for hanging thereto an end of a spring 27. 28 represents a U-shaped guide plate having upper and lower

bent portions 30 and 31 at both ends of the body 29, said bent portions having respectively grooves 32 and 33, and the body 29 is provided with an aperture 34 and vertical slits 35 and 36 at both sides of the aperture 34. The body 29 further has an arm 37 formed by bending at one side thereof, said arm having a mounting hole 38. 39 represents mounting screws for the guide plate 28 and 40 are washers.

41 is a sliding plate, which has metal arms 42 extending substantially in parallel to each other and having stepped shoulders 43 as bent at the upper portion. The shoulders 43 are coupled to a stopper plate 44 of insulating material located above. Said stopper plate 44 is provided at the upper portion with a pair of L-shaped drivers 45. Lower portions of the arms 42 are coupled to a leg 46 of insulating material. A hole 47 for mounting the other end of the spring 26 is made in the leg 46.

49 is an actuating lever for actuating the sliding plate 41. Lower portion of L-shaped body 50 of the lever is bent so as to form a locking arm 51, which has a cut-out 53 at the forward end. The other end of the body 50 forms an arm 52. The body 50 further has a mounting hole 54. A tubular member 55 carrying therein a shaft pin 56 is mounted on the lever 49 with the pin 56 inserted in the hole 54 through a washer 57.

58 is a gear wheel having adjacent its periphery a projection 59.

60 is a contacting member, comprising a supporting base 61 of insulating material, fixed contact arms 62 and upper and lower movable contact arms 63 and 64.

65 is a clutch arm, which is provided with a hole 66 extending through its body, in which a shaft 67 is inserted. 68 represents a spring carried on an extended end of the shaft 67. 69 is a clutch arm, where a hole 70 is made.

71 and 72 represent gear wheels connected to each other with a shaft 73.

Now, the assembled structure of the contact control mechanism will be explained with reference to FIGS. 4A, 4B and 4C and FIG. 5.

The yoke 13 for the electromagnet 10 is fixed to the base plate 7 and the lugs 14 on the yoke is loosely fitted in the cut-outs 16 of the armature 15, respectively. The actuating plate 18 is fixed preliminarily to the armature 15. The spring 27 is engaged at the right end with the projection 25 of the actuator 18, and at the other end with the projection 74 on the yoke 13. After passing the sliding plate 41 through the grooves 32, 33 in the guide plate 28 from the leg 46, the forward end 22 of the actuator 18 is inserted into the aperture 34 on the guide plate 28. The mounting screws 39 are inserted into the vertical slits 35 on the guide plate 28 through the washers 40, and the tops of the screws 39 are screwed in the holes 41' of the yoke 13.

Then, the contact member 60 is fixed to the base plate 7 at the side of the supporting base 61. The upstanding drivers 45 at the upper portion of the sliding plate 41 is disposed between the upper and lower movable contact arms 63 and 64.

Passing the shaft pin 56 through the mounting hole 38 of the arm 37 of the guide plate 28, through the tubular pipe 55 and through the mounting hole 54 in the actuating lever 49, the lever 49 is rotatably fixed to the guide plate 28. The gear wheel 58 is also rotatably mounted on the back of the dial case 1. The shaft 67 supported between the base plate 7 and the back of the dial case 1 is passed through the hole 66 in the clutch plate 65, and through the spring 68. The spring 68 is engaged at one end with the hole 74 in the clutch plate 65, and at the other end with a hole in the base plate 7. The shaft 73 is passed at an end carrying the gear 71 through the hole 70 of the arm 69 of the clutch plate 65 and at the other end carrying the gear 72 through a hole provided in the base plate 7. FIGS. 4A to 4C show such arrangement as above. Under this condition, the gear wheel 72 is in mesh with a gear wheel directly coupled to a motor 76 in the motor driving section A. The shaft 73 is born between the base plate 7 and the clutch arm 65. The gear wheel 71 is normally out of mesh with the gear wheel 58, since the clutch arm 65 is normally pushed up by a projection 20 of the actuating plate 18 (see FIG. 4C). The armature 15 joined integrally with the actuating plate 18 by

means of the spring 27 is normally separated from the core 12 of the electromagnet 10, and the forward end 22 of the actuating plate 18 is engaged with the stepped shoulders 43 of the sliding plate 41. Thus, the latter is biased downward by the resiliency of the spring 27. The drivers 45 of the sliding plate 41 are brought into contact at the lower edges thereof with the moving contact arms 64 and, thereby, the movable contact arms 63 carried on the upper edge of the drivers 45 are allowed to be in contact at their movable contacts 63' with the fixed contacts 62' so as to be ON state, whereas the other movable contacts 64' are kept in their OFF state. Further, under this condition, the actuating lever 49 is in engagement at the lower end tip of the locking arm 51 with the stepped shoulders 43 of the sliding plate 41, by the tension of a spring 75 which is fixed at an end and engaged at the other end to the actuating lever 49 so as to bias the same in the direction of an arrow shown in FIG. 6A, so that the sliding plate 41 is prevented from being moved upward, that is, the plate is locked in its lower position. The projection 59 of the gear wheel 58 at this time is spaced from the other arm 52 of the actuating lever 49. The above described state is shown in FIG. 6A.

Now, the operation of the relay according to the present invention will be described with reference to FIGS. 6A and 6B.

When an electric current is fed to the electromagnet 10 and to the motor with the dialing knob 2 set at a desired measurement, the motor is rotated and its rotation is transmitted to the gear wheel 71. When the core of the electromagnet 10 is excited and the armature 15 is attracted by the core, the armature 15 is pulled into engagement with the core against the biasing force of the spring 27. Since this also causes the projection 20 on the actuating plate 18 coupled to the armature 15 to be drawn toward the core, the arm 69 of the clutch arm 65 is sequentially made to swing toward the removed armature 15 due to the biasing force of the spring 68, so that the gear 71 on the shaft 73 supported by the arm 69 is brought into engagement with the gear wheel 58, thereby the wheel 58 is started to rotate. Consequently, the projection 59 on the wheel initiates to rotate in the direction of an arrow shown in FIG. 6B.

On the other hand, the forward end 22 of the actuating plate 18 is in its pulled-up position at this time due to the attraction of the armature 15, so that the sliding plate 41 is under the upward biasing force imparted by the spring 26 hung between the both plates 18 and 41. However, since the sliding plate 41 is still locked by the locking arm 51 of the lever 49 engaged on the shoulders 48, the sliding plate 41 cannot be moved upward.

After the laps of the preset desired time period, the rotating projection 59 of the gear wheels 58 abuts against the arm 52 of the actuating lever 49, so that the lever 49 is swung and its locking arm 51 is moved away from the shoulders 48, thereby the locking engagement of the lever 49 with the sliding plate 41 is released and, thus, the sliding plate 41 is caused to move upward due to the spring 26. Consequently, the drivers 45 on the sliding plate 41 thus lifted allow the both upper and lower movable contact arms 63 and 64 to be simultaneously shifted upward, so that the contacts 62' and 64' will be in ON state while the contacts 62' and 63' will be in OFF state.

Now, various features of the relay according to the present invention will be described.

According to the present invention, the time limit relay having the above described structure can be assembled more easily with a higher reliability, since the motor driving section A is disposed at one side of the base plate 7 and the contact control section B is disposed at the other side of the base plate, in particular, the latter contact control section B being assembled in such that the electromagnet 10 laterally fixed to the base plate 7 is associated at one end with the armature 15 as mounted to the yoke 13 and at the other end with the sliding plate 41 through the guide plate 28 fixed to said end, said sliding plate 41 is adapted to move upward and downward in response to the attraction and deattraction of the armature 15 through the

actuating lever 18 extending over the electromagnet 10 and integrally coupled to the armature 15 for controlling the contact operation of the contact arms 62-64 disposed above the electromagnet 10, and the sliding plate 41 normally locked by the actuating lever 49 pivoted to one side of the guide plate 28 is released by the actuation of the lever 49 at a preset limited time by the rotation of the motor when the armature is attracted.

According to the invention, further, the relative position of the guide plate 28 to the electromagnet 10 can be selectively varied so as to allow gaps between movable and fixed contacts to be freely adjusted, since the plate 28 is fixed through the vertically extending slits 35 provided in the body 29.

The sliding plate 41 according to the present invention is slidably mounted in the upper and lower grooves 32 and 33 of the guide plate 28 and is normally biased upward by means of the spring 26 coupling the plate 41 and the actuating plate 18. The engaging end 22 of the latter plate 18 in turn is normally biased downward by the spring 27 and the sliding plate 41 is locked in its consequential downward position by the locking arm 51 of the actuating lever 49. Such downward movement and upward movement when the lock is released of the sliding plate 41 is occurred in the both grooves 32, 33 and, thus, the upward and downward moving directions of the plate 41 are always accurate. In combination with the adjustable feature of the guide plate 28, thus, it is possible to obtain stable contact pressure even after repeated use and to have the ON-OFF contact operations carried out successively for many times in the accurate manner.

According to the present invention, the actuating lever 49 is rotatably fixed to the integral arm 37 of the guide plate 28, so that the relative opposing position of the locking arm 51 of the lever 49 to the shoulders 48 of the sliding plate can be adjusted simultaneously integrally with the guide plate 28, while maintaining the position of the arm 51 always in the most suitable relation to the shoulders 48. Thus, it is possible to achieve accurate timed operation of the contacts without any faulty operation.

Further according to the present invention, as shown in FIGS. 7A and 7B, the angle α formed by a line connecting between both holes 70 and 66 in the clutch arm 65 and a line connecting between the hole 70 and the rotary center of the gear wheel 58 is made to be greater than an angle β formed by the line between the hole 70 and the rotary center of the wheel 58 and a line Z of engaging action of the both gear wheels 58 and 71. With this arrangement, the both gears 58 and 71 are kept in their strong engagement during when the gear 71 is transmitting the driving force to the wheel 58 even with a smaller pressure imparted from the gear 71 to the wheel 58. Thus, it is possible to rotate manually the wheel 58 for varying the setting of the time limit only with a small force required while the wheel is being rotated by the motor. Thus, there are applied no unduly extra pressing and turning forces to the both gear wheels, whereby any fluctuations or changes of the gear rotation due to peeling-off or wearing of gears or damages thereof by external shock are prevented from occurring.

Discussing the above more in detail with reference to FIG. 7, FIG. 7A shows how the both gear wheels 58 and 71 are engaged to each other and how the rotating force of the motor is transmitted from the latter to the former. When the rotating force is thus conveyed, a force F as a reactive force is applied in the direction of a line of action Z to the gear face of the gear wheel 71 by the gear wheel 58. Component force F_n of the force F occurring in the direction at right angle with the connecting line between the rotary centers of the gear 71 and the clutch arm 65 is shown to be a force pulling the gear 71 as a driving gear into engagement with the wheel 58 as the follower gear. Thus, after the both gear wheels are once brought into engagement with each other, the gear wheel 71 does not fail this engagement. This results in that the clutch arm requires only a spring force which is good enough to bias the arm in counterclockwise direction when the arm is swung so as to

bring the gear 71 into engagement with the wheel 58. Thus, the impact force given to these gears is small and, consequently, any possible wear or damage occurring thereto can be effectively reduced.

FIG. 7B shows relations of the forces in the case when the time-limit setting is changed intentionally to make the remaining limited time to be shorter during the time-limiting operation is carried on with respect to the both gear wheels 58 and 71 in engagement with each other. When the gear wheel 58 is rotated in the direction of the arrow for changing the time limit setting, the rotating force will act as represented by a force F_1 on the gear face of the gear wheel 71 which is in mesh with the wheel 58 in the line of action. Component force F_{1a} of the force F_1 in right angle to a line connecting the respective rotary centers of the gear wheel 71 and the clutch arm 65 will become a force that pushes up the gear wheel 71. Accordingly, this force acts in the direction that the gear wheel 71 is disengaged from the gear wheel 58 of the follower side and, thus, the change of time limit setting is enabled without transmitting such external rotating force applied to the wheel 58 to the motor.

What is claimed is:

1. A time limit relay comprising a motor driving section fixed to one side of a base plate and a contact control section fixed to the other side of said base plate and adapted to receive from said motor driving section its rotary force, said contact control section comprising an electromagnet fixed to said base plate, an armature rotatably mounted to an end of the yoke of said electromagnet, an actuator integrally coupled to said armature, said actuator being disposed above the electromagnet and extending in longitudinal direction from said end to the other of the electromagnet as terminating at a free end, a guide means mounted to said other end of the electromagnet, and a sliding plate arranged slidably along said

guide means, said sliding plate being engaged at the upper section with forward free end of respective contact arms of a contact mechanism disposed above and in longitudinal direction of the electromagnet and at the lower section with a locking mechanism for the sliding plate which operatively cooperates with a follower gear wheel driven as coupled to the motor driving section being driven, and said sliding plate being actuated by said free end of the actuator.

2. A time limit relay according to claim 1, in which said 10 guide means is provided at both sides of its body part with a pair of vertical slits extending parallelly to each other, and is mounted to the yoke of the electromagnet by means of screws respectively passed through said slits.

3. A time limit relay according to claim 1, in which said 15 free end of the actuator is adapted to abut an upper stepped shoulder provided in the sliding plate, and said actuator and sliding plate are coupled together through a compression spring means.

4. A time limit relay according to claim 1, in which said 20 guide means is provided with an integral arm, and said arm supports rotatably an actuating lever having a locking arm adapted to engage and disengage a lower stepped shoulder provided in the sliding plate.

5. A time limit relay according to claim 1, in which said 25 locking mechanism is driven through a clutch arm rotatably supporting a driving gear at its rockable arm end, and said clutch arm is arranged in such that an angle α formed between a line connecting the rocking center of the clutch arm and the rotary center of said driving gear and a line connecting said 30 driving gear rotary center and the rotary center of the follower gear wheel is larger than an angle β formed between said line connecting the driving gear rotary center and a line of action Z of meshing engagement of the both gears.
